MEANS FOR SUPPORTING ELECTRODES IN IONIC TUBES.

1,330,935.

Specification of Letters Patent.

Patented Feb. 17, 1920.

Application filed June 29, 1918. Serial No. 242,518.

To all whom it may concern:

Be it known that I, FREDERICK PERCY DRIVER, a subject of the King of Great Britain, residing at London, England, have 5 invented new and useful Means for Supporting Electrodes in Ionic Tubes, of which the following is a specification.

This invention relates to means for supporting electrodes within ionic tubes such as 10 are used more particularly in wireless telegraphy, and has for object to provide, in combination with a substantially cylindrical anode, improved supporting means therefor adapted to obviate the chief difficulties incidental to the methods and devices heretofore usually employed for a similar purpose.

According to the present invention the anode cylinder, which is supported from 20 both ends of the ionic tube, is provided at each end with a set of longitudinally-extending carrier-bars attached on the one hand to the anode cylinder and on the other hand to a metal collar which is received in an annular seating formed within the tube at or 25 near the point where the corresponding neck of the tube opens into the bulb; the seatings at the respective ends of the tube being of such diameter relatively to the adjacent 30 necks as to present, endwise, oppositely-directed annular shoulders adapted to prevent longitudinal displacement of the anode and its attached supports in either direction after 35 their insertion in position, while lateral displacement is prevented by the engagement 40 of the collars with the inner peripheries of the seatings, with which one or both of the collars may be adapted to establish expanding spring contact.

In the accompanying drawings, Figure 1 is a side elevation of an ionic tube illustrating the mode of supporting a cylindrical anode therein in accordance with the present invention, a portion of each end of the 45 tube being in section, while the cathode and its supports are omitted. Figs. 2, 3 and 4 are separate edge views of three different forms of collar constituting part of the anode support; and Fig. 5 is a detail of a 50 portion of the collar shown in Fig. 4.

Referring to Fig. 1 and to the form of collar illustrated in Fig. 2, it will be seen that the anode cylinder *a* has riveted to it, near each of its ends, a set of three light

metal carrier-bars *b* which are equally 55 spaced around the circumference of the cylinder, the bars of the two sets, which respectively extend lengthwise of the cylinder axis in opposite directions, being riveted by their divergent outer ends *c* to two collars *d*, *d* each constituted by a split cylindrical band of elastic sheet metal which tends to expand to an effective diameter greater than that of the corresponding annular seating provided for it in the tube. Each neck *e* 60 of the tube has an internal diameter sufficient to give passage to the anode cylinder *a*, and is joined to the corresponding end of the bulb *f* by a short cylindrical enlargement *g* which opens directly into the bulb 65 and, at its junction with the neck, presents a shoulder *h*; the distance between the shoulders *h*, *h* at the respective ends of the bulb corresponding to the total length of the anode-structure constituted by the anode 70 cylinder *a* with its carrier-bars *b*, *c*, and collars *d*, *d*, so that on compressing or contracting the collars *d*, *d* sufficiently to permit of their passing through one of the necks *e*, the entire anode-structure may be 75 slipped lengthwise into its required position within the tube, wherein it will be securely retained by the elastic expansion of the now released collars *d*, *d* within the respective neck enlargements *g*, *g*.

In order, when the anode-structure has been placed in position, to prevent such accidental contraction in the diameter of the collars *d*, *d* (e. g. in consequence of jarring or vibration) as might result in displacement of the anode-structure, the ends of the split cylindrical band constituting a collar may, after the expansion of the collar within its annular seating, be locked together, as for example by means of a headed stud *j* 85 fixed near the one end engaging in a key-hole-slot *k* provided near the other end of the band, as in Figs. 4 and 5.

If desired, a collar, instead of being split as above described, may be constituted, as 100 shown at *l* in Fig. 3, by a permanently closed annulus of less external diameter than the bore of the corresponding neck *e*: a series of (say, three) outwardly-extending elastic tongues *m* being formed upon or attached to 105 the collar *l* so as, on the one hand, to be capable of being compressed to permit introduction of the collar into the neck of the

tube and, on the other hand, to be adapted to spring outward against the inner periphery of the neck-enlargement *g*.

In some cases, as for example where the tube has only a single neck, or where it is desired to make the neck at one end of the tube of smaller bore than would be convenient for giving passage to the anode cylinder, the annular seating at the end remote from that neck through which the anode structure is to be entered may be of so much smaller diameter than the seating at the entering end, as to permit of the corresponding smaller collar being made capable of being passed through the entering neck without contraction. In such cases the collar of smaller diameter may be a permanently closed annulus adapted to fit closely within its seating in the corresponding neck enlargement, either with or without the employment of spring tongues or equivalent devices, whereas the collar of larger effective diameter, which is at the opposite end, may be made capable of a substantial amount of contraction and of being sprung into position as previously described.

Having now particularly described and ascertained the nature of my said invention and in what manner the same is to be performed, I declare that what I claim is:—

1. Means for supporting a substantially cylindrical anode in an ionic tube, comprising two sets of longitudinally extending carrier-bars attached to the anode at its opposite ends and respectively extending therefrom in opposite directions, and metal collars attached to the outer ends of the respective sets of carrier-bars and adapted to

be received in annular seatings formed within the tube at the corresponding ends of the latter, substantially as set forth.

2. Means for supporting a substantially cylindrical anode in an ionic tube, as claimed in claim 1, wherein the metal collar attached to the outer ends of a set of carrier-bars is constituted by a split cylindrical band of elastic sheet metal which tends to expand to an effective diameter greater than that of the corresponding annular seating provided for it in the tube, substantially as described. 45

3. Means for supporting a substantially cylindrical anode in an ionic tube, as claimed in claim 2, wherein the ends of the split cylindrical band constituting a collar are provided with devices for enabling them 55 to be locked together after the expansion of the collar within its annular seating, substantially as described.

4. An ionic tube for use with supporting means for a substantially cylindrical anode, 60 said ionic tube having at its ends annular seatings adapted to receive the metal collars attached to the corresponding outer ends of the respective sets of anode carrier-bars and to present, endwise, oppositely-directed annular shoulders for preventing longitudinal displacement of the anode-structure as a whole, substantially as set forth. 85

5. An ionic tube as claimed in claim 4, wherein the annular seatings at the ends of 70 the tube are constituted by enlargements of the diameters of the respective necks of the tube where said necks open into the bulb, substantially as described.

FREDERICK PERCY DRIVER.
